UNITED STATES PATENT OFFICE.

WILHELM BAHRE, OF BERLIN, GERMANY.

DOOR-CHECK.

SPECIFICATION forming part of Letters Patent No. 320,527, dated June 23, 1885.

Application filed September 16, 1884. (No model.)

To all whom it may concern:

Be it known that I, WILHELM BAHRE, a subject of the King of Prussia, residing at Berlin, Prussia, German Empire, have invented 5 certain new and useful Improvements in Apparatus to Close Noiselessly Doors, of which the following is a specification, reference being had therein to the accompanying drawings.

This invention relates to mechanism for preventing the slamming of doors; and it consists, principally, in the combination of a sliding rod, which has a head and is carried by a door with a guide attached to the door-jamb, which throws said rod upward when the door 15 is closed violently, and a spring arranged to receive the impact of said head when the rod is thus thrown up, for the purpose of checking the door and preventing noise, all as herein-after particularly set forth and claimed.

20 In the accompanying drawings, Figure 1 represents in front elevation a part of a door and door-frame provided with my improved devices for preventing slamming. Fig. 2 represents a side view of the same, the top of the 25 door-frame and the spring attached thereto being shown in section. Fig. 3 represents a view similar to Fig. 2, except that the rod and its head are shown raised into position for the latter to strike against said spring. Fig. 4 30 represents a view, similar to Fig. 1, of a modification of my door-slammimg-preventing devices. Fig. 5 represents a similar view of another modification thereof. Fig. 6 represents an edge view, and Fig. 7 a plan view, of substitute devices for the head and the elevating-guide and lever shown in Fig. 1. Fig. 8 represents an enlarged detail plan view of the 35 spring before mentioned. (Hereshown as provided with rubber cushions.) Fig. 9 represents a front view, Fig. 10 a plan view, and Fig. 11 a side view, of another modification of my invention.

In said drawings, A designates the door; B, the door-jamb; C, the top bar of the door-frame; 45 a, a plate secured to said door and provided with two outwardly-extending tubular bosses, b, which serve as guides and as means of attachment for a rod, c, which moves vertically up and down through them. The upper end 50 of this rod is provided with a head, d. A cord, e, connects the lower end of said rod c

with the outer end of a crank-arm, g', formed upon a horizontal crank-shaft, f, which turns in bearings f' f' attached to door A. This crank-arm in its normal position is horizontal, 55 extending directly out from the door, as shown in Fig. 2, and at the other end of said crank-shaft another crank-arm, g, is formed, which is first bent downward, then horizontally in a line parallel to the door, and extending beyond the same, so as to overlap an arm, h, 60 which extends outward from the door-jamb. This arm h is bent in the middle into the form of a broad inverted V. To the top bar, C, of the door-frame is attached a spring, l, which 65 is arranged to be struck by the head d of rod c whenever said head is raised sufficiently high.

When the arm g is brought gently into contact with arm h by the gradual closing of the 70 door, it will ride up the outer incline of the latter arm and then slip down the inner incline thereof, the crank-shaft f being turned but a short distance and the head d not being raised far enough to come opposite spring l; 75 but when the door is violently closed the arm g will strike so forcibly against the outer incline of arm h that the crank-shaft f will be turned far enough to throw the arm g' and rod c into the position shown in Fig. 3, bringing the head d opposite spring l. Said head then strikes against said spring and is thrown backward a little by the resiliency of the latter, thus preventing the noise and jar of 80 slamming the door. This spring l is preferably bow-shaped, having one end fast and the other free, pads or cushions i k being provided at the point of contact, as shown in Fig. 8.

Instead of the crank-shaft f, I may, as shown 90 in Fig. 4, use a lateral extension, m, of the lower end of rod c, the arm h being located at a lower point on the door-jamb than in Figs. 1, 2, and 3, in order to be struck by said extension. A guide, n, attached to the door, 95 keeps said extension m in proper position for operation as it rises and falls. The cord e is of course dispensed with.

Another modification (shown in Fig. 5) employs a lever, o, arranged under the rod c, but 100 not attached thereto, the guide n being employed, as in Fig. 4, and the operation being

the same as in the latter modification, except that contact is substituted for the motion of a single piece.

Another modification (illustrated in Figs. 6 and 7) consists of a frame, *p*, which is hinged to the top bar, *C*, of the door-frame below spring *l*, and provided with two downwardly-inclined parallel rods or bars, *q q'*, which leave a narrow channel or passage between them. This passage is wide enough to admit rod *e*, but not wide enough to admit the head *d*. In this modification the hemispheres making up said head are divided and arranged on said rod with their convexities toward each other. The rod *e* at their point of contact enters the passage between rods or bars *q q'*, and the upper hemisphere normally rides up the incline of said rods or bars, lifting them and frame *p* no more than is indicated by dotted lines in Fig. 6. When the door is violently shut, however, the force of impact between the hemispheres and the rods or bars *q q'* is such that the head *d* and frame *p* are both thrown upward until the head *d* passes beyond the rods or bars *q q'* into the wider opening *p'* in the body of the frame. Said frame is then free to fall, and the head *d* and rod *e* rising a little farther by their momentum, said head is brought into position to strike against spring *l*, with results as aforesaid.

In the modification shown in Figs. 9, 10, and 11, the rod *e* does not slide, but turns axially, and is provided at its upper end with horizontal arm *r* having pad *t*, and at its lower end with another horizontal rod, *s*, these rods extending in reversed direction and being normally parallel to the plane of the door. A

spring, *u*, bearing against arms *s*, tends to hold them in this position or return them thereto if they have been forced out of it. A bar, *v*, is hinged to a bracket, *v'*, fastened on the door-jamb, said bracket preventing said hinged bar from turning toward the jamb beyond the vertical position, but allowing said bar to turn freely in the opposite direction. When the door closes, arm *s* strikes against bar *v*, and shaft or rod *e* is thereby turned, so as to bring the pad *t*, which is on the free end of arm *r*, against the spring *l*, as shown in Fig. 10. The door rebounds a little by reason of the resiliency of said spring. The spring *u* brings the rod or shaft *e* and its arms *r s* back into the position shown in Fig. 9, and the door closes easily. When the door is opened, the pressure of arm *s* against hinged bar *v* causes the latter to turn outward sufficiently to allow the passage of said arm, as shown in Fig. 11.

Having thus fully described my invention, what I claim as new, and desire to secure by Letters Patent, is—

A rod, *e*, provided with a head *d*, and attached to a door, in combination with a spring attached to the door-frame and arranged to be struck by said head and an arm attached to said door-frame, and operating to throw said rod into position for said head to be engaged by said spring, substantially as set forth.

In testimony whereof I affix my signature in presence of two witnesses.

WILHELM BAHRE.
